UNITED STATES PATENT OFFICE.

WILLIAM H. MCNARY, OF BROOKLYN, NEW YORK.

IMPROVEMENT IN CONVERTING MOTION.

Specification forming part of Letters Patent No. 35,883, dated July 15, 1862.

To all whom it may concern:

Be it known that I, WILLIAM H. MCNARY, of the city of Brooklyn, in the county of Kings and State of New York, have invented a new and Improved Mechanism for Converting Motion; and I do hereby declare that the following is a full, clear, and exact description of the same, reference being had to the accompanying drawings, forming part of this specification, in which—

Figure 1 is a front view of my improved mechanism having the front gear removed to show the construction of the parts behind it. Fig. 2 is a back view of the front gear. Fig. 3 is a vertical section of the mechanism at right angles to Fig. 1. Fig. 4 is a perspective view of part of the reversing device.

Similar letters of reference indicate corresponding parts in the several figures.

This invention consists in certain means applied in combination with a driving-shaft rotating continuously in one direction, whereby the said shaft may be made to impart rotary motion to machinery either in one direction or the other, and to reverse the direction automatically at such intervals of time, however irregular, as may be desired.

To enable others to make and use my invention, I will proceed to describe its construction and operation.

A is the driving-shaft, fitted to bearings *a a*, and supposed to have a rotary motion in the direction of the arrow shown upon it in Fig. 3. This shaft has fast to it what I call a "switch-wheel," D, which gears with and drives a toothed gear, B, which is arranged to turn freely upon a fixed stud, *b*, secured in a position transverse to the shaft A in a stationary box, C, the movable front plate, *c*, of which is omitted in Fig. 1, and the upper part of which is represented in that figure as being broken away to expose the switch-wheel fully to view. The box has an opening in the back to admit a portion of the switch-wheel.

The switch-wheel D has formed upon its circumference two threads, *f f*, of a width and depth to fit the spaces between the teeth of the gear B, such threads running about or a little more than three-fourths of the way round the circumference in planes parallel with its planes of revolution, and the remaining fourth of the circumference being cut away to receive a

movable piece or switch, D', on which is formed a thread, *f'*, which is capable of forming a connection in either direction oblique to the plane of revolution between one and the other of the two threads *f f*, the said switch being fitted to turn on a pivot, *g*, to permit the direction of its obliquity to be reversed. The gear B remains stationary while the threads *f f* are passing between its teeth, but is caused to rotate a distance equal to the pitch of its teeth while the thread *f'* is passing, such rotation being in one or the other direction according to the direction of the obliquity of the thread *f'*. As often as the switch is shifted, the direction of the rotation of the wheel B is changed, the direction of the rotation of the shaft A being the same. The switch is locked in either position partly by one of two buttons, *h h'*, that are attached firmly to the same pin, *i*, running through the wheel D in a direction parallel with the shaft, and partly by a fixed stop, *o*, arranged within the wheel behind or under the switch to limit the movement of the latter upon the pivot *g*. This stop *o* is only shown in dotted outline in Fig. 3 of the drawings; but the buttons are shown in Figs. 1, 3, and 4, Fig. 4 exhibiting them and their connection - pin *i* separate from the wheel. One button turns the switch in one direction and locks it in that direction, and the other turns and locks it in the other direction, the said buttons being arranged at right angles to each other, so that both are never in operation at once. The buttons are made to shift the switch by the cam-like action of bevels *6 6*, provided on their inner sides, upon bevels *7 7*, provided on opposite corners of one end of the switch, the turning of the buttons to produce their cam-like action being produced by their being brought by the revolution of the switch-wheels into contact with one or other prong of a forked lever, E, which works, parallel with the rotation of the gear B, on a fulcrum-pin, *d*, attaching it to the back of the box C. The space between the two prongs *e e'* of the fork of this lever is wide enough to admit the thickness of the switch-wheel and one of the buttons *h h'*, and the said lever is so arranged that whichever button is in a position to lock the switch in the manner illustrated by *h* in Fig. 3 would clear its respective prong of the fork in the revolution of the wheel, but that

the other button would come in contact with its respective prong if the latter were nearly close against the side of the wheel. The movement of the said lever E is limited by the opening k, which is provided in the back of the box C for a projection, l, on the front of the said lever to work in, such movement being sufficient to allow either prong to come nearly into contact with the side of the switch-wheel, and the said lever is prevented from remaining in any position but at the extreme end of its movement by means of a spring, F, with a V-shaped tooth, j, at its end, secured to the back of the box B, such tooth engaging in one or other of two V-shaped notches that are provided on either side of a V-shaped projection on the back of the lever. The spring-tooth, however, yields to any considerable pressure on either side of the lever, and so permits it to be moved from one to the other position, as desired. On moving the lever to either position the prong e or e' which has arrived near the wheel catches its respective button as the latter comes round with the wheel, and by shifting the button causes the switch to be unlocked, shifted, and relocked, the unlocking being effected by the movement imparted to the opposite button before the button which is immediately acted on by the lever comes into contact with the switch. When the switch has been shifted, the buttons occupy such positions that they will revolve clear of the lever until the position of the lever is changed, and hence the change in the direction of the revolution of the gear B is effected by changing the position of the lever E.

I will now proceed to describe the automatic means of shifting the lever E, which constitute the essential features of my invention.

G G are pins fitted to work through holes in the gear B parallel with but at different distances from the axis thereof. These holes are deeply countersunk from the front side of the wheel for the reception of spiral springs m, Fig. 3, which are coiled round the pins, and of collars n, provided upon the said pins for the springs to press against for the purpose of drawing back the pins within the back of the gear B, and thereby preventing them from striking the projection l on the back of the lever in their revolution with the wheel. The said pins are secured in the holes by a covering-plate, H, screwed to the face of the curved projection made on the front of the wheel to give it the thickness required where the pins G G pass through it. The springs m m hold back the collars n of all the pins against the plate H, except when one is pushed back by means of one of a series of wedge-like projections, s s, attached to the back of the toothed wheel I, which is fitted to turn freely on the hub of the gear B, and thereby made to protrude through the back of the gear B far enough to strike the lever E in its revolution, and thereby effect the shifting of the switch and reversal of the gear B. This toothed wheel I has gearing with it a pinion, J, which is fitted

to turn on a stud, p, that is fast in the gear B near the periphery thereof. This pinion has fastened to its back a square plate, q, so arranged that either of its sides will run in contact with a circular way, r, provided in the interior of the box C, which is concentric with the gear B and wheel I, and so prevent the said plate and the pinion from being turned on the stud at any point in the revolution of the gear B and wheel I, except at r' r', where there is an opening formed in the way r for the plate to turn in, and a fixed tooth, t, arranged to catch between the teeth of the pinion for the purpose of turning the latter a quarter of a revolution on the stud p, and so causing it to turn the wheel I a short distance relatively to the gear B, by which means the wedges s s are from time to time, as may be desired, caused to act upon the pins G G, one at a time, to make them protrude far enough through the back of the wheel to strike the projection l of the lever E, and so cause the reversal of the switch and of the revolution of the gear B. As soon as a wedge s passes a pin G on which it has acted, the pin is withdrawn within the back of the gear by its spring m.

The pins G G have been described to be at different distances from the axis of the gear B; and it is obvious that the wedges s s must be arranged at distances from the axis of I corresponding with the distances of the pins from the axis of B. One, two, or more wedges may be arranged in the same circle, according to the frequency with which the reversal is desired. Except at the time of passing the opening r' r' and tooth t, the gear B and wheel I are locked firmly together, and no change takes place in the relation between the pins G G and the wedges s s.

In order that the tooth t may only operate while the gear B and wheel I rotate in the direction of the arrow shown on B in Fig. 1, the said tooth is formed upon a slide, K, that is fitted to slide in the opening r' r' in a direction parallel with the axis of the gear B and wheel I. This slide has applied to it a spring, u, which tends to hold it back to the position shown in Fig. 3, in which it is in range of the pinion J; but there is attached to the front of the gear B, behind the pinion J, an oblique-faced cam, v, composed of a spring so constructed and applied that in turning in the opposite direction to that indicated by the arrow shown in Fig. 1 it will pass behind a projection, y, on the back part of the slide, and so be caused to force the said slide forward and hold it there with the tooth t in front of and out of range with the pinion J. When the gear B turns in the direction of the arrow, the cam v passes over the projection y, leaving the slide with the tooth t in range of the pinion.

The slide K is so constructed that when its tooth t is in advance of and out of range with the pinion J a portion, r², of the surface of the said slide forms a continuation of the way r to prevent the plate q and the pinion from turn-

ing. While no movement of the wheel I relatively to the gear B takes place the pins G remain fixed, and if one is projecting through the back of the gear B the said gear and the wheel I will make nearly a complete revolution back and forth, the projecting pin causing the switch to be shifted as it strikes first one and then the other side of the lever E; or, if two the pins G G project, the reversal of the switch and gear will take place at more frequent regular intervals, according to the number of degrees of a circle at which the pins are apart.

The gear B may be the gear through which motion is transmitted from the switch-wheel to the machinery to be driven, or may constitute simply a portion of the mechanism for converting or reversing the rotary motion of the said machinery, a separate gear gearing with the switch-wheel being in the latter case used for transmitting motion to the machinery.

The invention is not limited in its application to a switch-wheel, D, on the driving-shaft, as, for instance, the same effect as is produced by the switch-wheel—viz., the automatic reversal of the machinery to be driven at such intervals as may be desired without reversing the driving-shaft may be effected by means of two bevel-gears facing each other upon the driving-shaft and turning therewith, and a third bevel-gear so arranged upon the shaft to be driven and between the two first mentioned that by shifting them upon the driving-shaft one or other may be brought into gear with the gear on the shaft to be driven. In this case the lever E would be applied to shift the two bevel-gears upon the driving-shaft to throw one or other of them in gear;

and the third bevel-gear is a substitute for the gear B.

Some modifications of the parts of the reversing mechanism may be made—as, for instance, the pins G G may be attached to springs composed of strips of steel secured to and radiating from the hub of the gear B, and the wedges may consist of beveled recesses in the outer face of the wheel I, and instead of the pinion J there may be substituted to operate between the gear B and wheel I a short pawl-lever attached to the gear B and actuated by passing over a fixed tooth or cam provided in the box C, to produce the same effect as the pinion J produces in passing over the tooth t, the point of the said pawl-lever acting on the teeth of the wheel I in substantially the same manner as the teeth of J act upon it.

What I claim as my invention, and desire to secure by Letters Patent, is—

The employment, in combination with a switch-wheel or other equivalent device carried by a driving-shaft, of a gear, B, and toothed wheel, I, the said gear carrying pins G G, controlled by springs, and the said toothed wheel being furnished with wedges s s, or other inclined surfaces of similar character, and the said gear and toothed wheel being connected by a pinion, J, or its equivalent, actuated by a fixed tooth, t, the whole combined and applied to operate upon the reversing-lever E or other device for reversing the motion substantially as herein specified.
